H. E. LINDBLADH

APPARATUS FOR CONTROLLING SHEETS

Filed July 5, 1921

UNITED STATES PATENT OFFICE.

HARMON E. LINDBLAHD, OF BROOKLINE, MASSACHUSETTS, ASSIGNOR TO THE LINDBLAHD CORPORATION, A CORPORATION OF MASSACHUSETTS.

APPARATUS FOR CONTROLLING SHEETS.

Application filed July 5, 1921. Serial No. 482,587.

In feeding sheets of paper or similar material to various machines, of which ruling machines furnish an example, it is desirable to overlap the successive sheets to effect their more perfect control by the gate or like mechanism which stops and releases them in timed relation for delivery to the mechanisms which are to operate upon them. This is a recognized procedure in manual feeding, and is accomplished automatically by means which is the subject of my application Ser. No. 436,970, filed March 13, 1921, wherein the advantages are fully discussed. Improved apparatus for performing this overlapping is herein described and claimed, this being of a highly simple and effective character, and possessing the especial merit of being readily put out of action, as by converting it into a simple conveyor, when the sheets need not be overlapped.

In the accompanying drawing, several of the many embodiments which my invention may assume are illustrated, Figure 1 being a perspective view of one form of my improved controlling apparatus; Fig. 2, a broken perspective showing the non-overlapping arrangement of the conveyor of Fig. 1; Fig. 3, a longitudinal sectional detail giving another form of the overlapping rolls; and Fig. 4 illustrating in broken perspective still another embodiment of the invention.

In oppositely spaced, suitably supported side-bars 10, 10 are journaled, near the ends, rolls 11, over which operates a conveyor, preferably furnished by spaced tapes 13. To one of these rolls power is applied in any convenient manner, as through the pulley shown, to advance the upper runs of the tapes in the direction of the arrow in Fig. 1. This conveyor may receive at one end sheets delivered by any feeder, as that disclosed in my Patent No. 1,258,028, dated March 5, 1918, this machine not being here illustrated. At the opposite or forward end, the conveyor discharges the sheets upon the cloth or conveyor 14 of what is here shown as a ruling machine, of this there appearing only, in addition to the cloth, the receiving roll 15 and the gate 16 with its operating cam-shaft 17. The elements shown correspond to those of the machine of Patent No.

1,242,823, issued in my name Oct. 9, 1917. Between the rolls 11, sliding upon the bars 10, are opposite bearing-blocks 18, 18, in which is journaled a shaft 19 extending at right angles to the side-bars and between the upper and lower runs of the tapes. Fixed upon the shaft 19, in the spaces between adjacent tapes, are rolls or shaft-enlargements 20, the length of which axially of the shaft is such that they do not interfere with the travel of the tapes, while the diameter is sufficient to cause them to project at their upper sides for a substantial distance above the upper runs of the tapes. The shaft and supported rolls are rotated by a belt 21, passing over the rolls 11 and driven by contact with the one to which power is applied, and also over a pulley 22 fast upon the shaft 19 and over a tightener or guide-roll 23 rotatable upon the lower portion of one of the blocks 18. The elements are so proportioned as to cause the rolls 20 to turn at greater peripheral speed than the rate of travel of the tapes. Preferably, the rolls are secured to the shaft by set-screws. This allows them to be adjusted transversely of the apparatus, and their relation to the sheets fed varied to obtain the best results.

Mounted to turn in the side-bars 10, at opposite sides of the bearing-blocks 19, are transversely extending shafts 24, 24, on each of which is mounted a pair of sprockets 25, 25, situated in close proximity to the inner faces of the side-bars. Over the longitudinally alined sprockets of these pairs operate chains 26, 26, the upper portions of which are secured at 27 to the tops of the bearing-blocks. Upon one of the shafts 24 is fixed a crank 28 to enable the operator to turn the shaft conveniently and, by the contact of its sprockets with the chain, shift the bearing-blocks simultaneously in one direction or the other along the bars. As the pulley 22 and roll 23 travel together, this will be accomplished without disturbing the relation of the belt 21 or varying its tension. This movement of the bearing-blocks, and consequently of the shaft 19 with its rolls 20, will alter the distance of said rolls from the gate 16 of the machine fed.

It will be seen that a sheet, as that designated by the letter A, is advanced along the conveyor-tapes 13 and is stopped by the

gate 16 of the ruling machine, partly upon the tapes 13 and partly upon the cloth 14, which would ordinarily be traveling at substantially the same speed. It may there be held by the gate, while the succeeding sheet B is carried by the tapes into contact at its forward extremity with the rolls 20. The curved peripheral surfaces of these rolls which project above the tapes are inclined upwardly at the side of contact in the direction of travel of the conveyors, and consequently the tendency is to deflect the sheet in this direction. This tendency is aided by the more rapid rotation of the rolls, which exert a force tending to lift and drag forward the end of the sheet, it assuming the position illustrated in Fig. 1, in which it is above the rear extremity of the preceding sheet which is being held by the gate. Then, as the gate rises and permits the advance of the sheet upon the cloth, as is indicated at C, the sheets A and B travel together in partially superposed relation, the rear sheet continuing under the feeding influence of the rolls 20 until the rear extremity has cleared them. The sheets A and B will thus be overlapped, and the gate, now lowered and resting upon the sheet A, will catch and arrest the sheet B with certainty, allowing plenty of time for said sheet to be brought by its contact into the correct angular position, and without danger of its being projected beneath the edge of the preceding sheet, in which position its progress could not be stopped by the gate. When sheets of another length are to be fed, the position of the rolls 20 may be suitably altered by turning the crank 28 in one direction or the other to change the space between the rolls and the gate. By this adjustment, the overlapping of sheets of any dimension within the capacity of the feeder may readily be effected.

When the so-called faint-line ruling is to be done, or that in which the lines extend entirely across the sheets, no sheet-arresting action is desired and the gate is put out of operation. Consequently, the overlapping device becomes unnecessary, and it may be rendered ineffective by its conversion into supports for the tapes, which now act merely as conveyors. To this end, the tapes are shifted upon the rolls 11 until they run over the peripheral surfaces of the rolls 20, instead of between them, as is illustrated in Fig. 2, and to enable them to be with certainty maintained in this position, guide devices are provided for the tapes. These preferably consist of forks 30 (Fig. 1), the arms of which are so spaced as to just permit the edges of the tapes to pass between them. The forks are mounted upon a spindle 31 extending transversely of the tapes and fixed at its ends in the side-bars. Set-screws 32 are shown as threaded through

the hubs of the forks for engagement with the spindle, this permitting the forks to be adjusted to and retained in the desired positions, giving the relation of the tapes which renders the overlapping rolls effective or ineffective.

If it is desired to obtain a more positive elevating effect than is given by the cylindrical rolls 20, there may be substituted for these, upon the shaft 19, rolls 35 having radial projections 36, of which four are illustrated in Fig. 3 of the drawing, separated by angles of 90 degrees. Each projection has converging opposite sides, which appear as curved in such a manner that they are inclined, as they initially receive and raise the sheets, upwardly in the direction in which these are traveling, offering little resistance to the forward movement and also giving the maximum lifting and advancing effect. The ends of the projections may be rounded at 38, so that when the overlapping function is to be nullified, the tapes may readily run upon them under the guidance of the forks 30, giving, as already described in connection with the form of Fig. 1, a mere conveying and not an overlapping effect.

For the rolls of Figs. 1, 2 and 3 there may be substituted the organization appearing in Fig. 4. Here the shaft 19 carries, instead of the rolls 20, grooved pulleys 40, over which run elevating-conveyors, furnished by endless strings or belts 41. The forward ends of these elevating strings, in the direction of advance of the sheets, are supported by grooved pulleys 42, rotatable about a shaft 43 journaled in the outer extremities of arms 44 pivoted about the shaft 19 just inside the bars 10. The height of the pulleys may be determined and varied by means of a screw 45 threaded into the shaft 43 and passing through an arcuate slot in one of the bars. This screw may be turned into contact with the bar to fix the shaft 43 and pulleys 42 in position. When these are raised to their maximum height with the shaft just beneath the upper runs of the tapes, the strings 41 will furnish inclined, traveling elevating surfaces, generally equivalent in action to the rolls 20 and 35. If the overlapping effect is not desired, the shaft 43 is lowered until the upper portions of the pulleys, and consequently the strings, are below the tapes, the latter now presenting a horizontal conveying surface, and the overlapping device being out of action. Rotation of the shaft 19 for the purpose of driving the elevating strings and adjustment of the blocks 18 for different sizes of sheets may be obtained in this instance in the same manner as in the form of Fig. 1.

I claim:

1. In an apparatus for controlling sheets, means for advancing successive sheets, and

means associated with the advancing means for elevating the forward extremity of each sheet upon said advancing means above the preceding sheet, said elevating means thereafter remaining in contact with the sheets throughout their lengths.

2. In an apparatus for controlling sheets, means for advancing the sheets, and sheet-elevating means receiving sheets from the advancing means and co-operating with said advancing means to overlap the sheets, said elevating means contacting with said sheets throughout their lengths.

3. In an apparatus for controlling sheets, means for advancing successive sheets, and rotatable means associated with the advancing means and having a peripheral portion arranged to engage and elevate the forward extremity of each sheet above the preceding sheet.

4. In an apparatus for controlling sheets, means for advancing successive sheets, overlapping means to which sheets are forwarded by the advancing means, and co-operating with said advancing means to effect the overlapping, both the advancing and overlapping means being movable, and means for moving the overlapping means more rapidly than the advancing means.

5. In an apparatus for controlling sheets, means for advancing successive sheets, movable engaging means to which sheets are forwarded by the advancing means, and means for moving the engaging means more rapidly than the advancing means, said engaging means being arranged to elevate the forward extremity of each sheet above the end of the preceding sheet upon the advancing means.

6. In an apparatus for controlling sheets, means for advancing the sheets, sheet-overlapping means co-operating with the advancing means and arranged to elevate the forward end of each advancing sheet, and means arranged to position the overlapping means longitudinally of the advancing means.

7. In an apparatus for controlling sheets, means for advancing successive sheets, movable sheet-engaging means associated with the advancing means, means for moving the engaging means to elevate the forward extremity of each sheet above the end of the preceding sheet, and means arranged to adjust the position of the elevating means and a portion of the moving means with relation to the advancing means.

8. In an apparatus for controlling sheets, separate endless sheet-conveyors, and overlapping means for the sheets extending between and above the upper runs of the conveyors.

9. In an apparatus for controlling sheets, separate sheet-conveyors, and overlapping means for the sheets extending between the

conveyors and having a surface arranged for engagement with the forward ends of the sheets and inclined upwardly in the direction of advance of said sheets.

10. In an apparatus for controlling sheets, 70 separate sheet-conveyors, and overlapping means for the sheets extending between the conveyors and having a sheet-engaging surface movable in contact with the sheets in the direction of advance of said sheets.

11. In an apparatus for controlling sheets, 75 separate endless sheet-conveyors, overlapping means for the sheets extending between and above the upper runs of the conveyors and having a sheet-engaging surface inclined 80 in the direction of advance of the sheets, and means for moving said surface in the direction of advance of the sheets.

12. In an apparatus for controlling sheets, 85 separate sheet-conveyors acting simultaneously to advance such sheets, overlapping means extending between the conveyors, said overlapping means being arranged to contact with the forward edge of each sheet, and means arranged to vary the position of the overlapping means longitudinally of the conveyors.

13. In an apparatus for controlling sheets, 90 separate endless sheet-conveyors, and means extending between and above the upper runs 95 of the conveyors and arranged to elevate the forward extremity of each sheet over the rear of the preceding sheet.

14. In an apparatus for controlling sheets, 100 separate sheet-conveyors, means extending between the conveyors and arranged to elevate the forward extremity of each sheet over the rear of the preceding sheet, and means for moving the elevating means in contact with the sheets in the direction of advance of said sheets.

15. In an apparatus for controlling sheets, 110 separate sheet-conveyors, means extending between the conveyors and arranged to elevate the forward extremity of each sheet over the rear of the preceding sheet, and means arranged to adjust the elevating means longitudinally of the conveyors.

16. In an apparatus for controlling sheets, 115 a conveyor, means for stopping the advance of a sheet upon the conveyor, and means arranged to elevate the succeeding sheet above the end of the stopped sheet.

17. In an apparatus for controlling sheets, 120 a conveyor, means for stopping the advance of a sheet upon the conveyor, and means movable to elevate the succeeding sheet above the end of the stopped sheet.

18. In an apparatus for controlling sheets, 125 a conveyor, means for stopping the advance of a sheet upon the conveyor, means arranged to elevate the succeeding sheet above the end of the stopped sheet, and means arranged to vary the distance between the elevating means and the stopping means.

19. In an apparatus for controlling sheets, separate sheet-conveyors, and members projecting between the conveyors and arranged to contact with the sheets to raise them from the conveyors.
20. In an apparatus for controlling sheets, separate sheet-conveyors, members projecting between the conveyors and arranged to contact with the sheets to raise them from the conveyors, and means arranged to stop the advance of the sheets when the rear extremity is in proximity to the raising means.
21. In an apparatus for controlling sheets, a sheet-conveyor, sheet-overlapping means associated therewith, and means arranged to render the overlapping means temporarily ineffective.
22. In an apparatus for controlling sheets, a sheet-conveyor, and sheet-overlapping means associated therewith, the conveyor and overlapping means being arranged for relative movement to render said overlapping means temporarily ineffective to overlap the sheets.
23. In an apparatus for controlling sheets, a sheet-conveyor, sheet-overlapping means associated therewith, and means arranged to retain the conveyors in position to render the overlapping means effective or ineffective.
24. In an apparatus for controlling sheets, separate sheet-conveyors having upper and lower runs, and sheet-overlapping members constructed and arranged to act between the upper runs of the conveyors in the performance of the overlapping function and between the upper and lower runs to render them ineffective to overlap the sheets.
25. A sheet-controlling apparatus comprising separate endless traveling conveyors, and rotatable overlapping members extending at all times in the overlapping action between the conveyors for engagement with the sheets.
26. A sheet-controlling apparatus comprising separate endless traveling conveyors, and rotatable overlapping members extending between the conveyors and having peripheral portions in constant engagement with sheets traveling over them.
27. A sheet-controlling apparatus comprising separate endless traveling conveyors, rotatable overlapping members extending between the conveyors for engagement with the sheets throughout their advance, and means for driving the conveyors and overlapping members at different speeds.
28. A sheet-controlling apparatus comprising separate endless traveling conveyors, rotatable overlapping members extending between the conveyors for engagement with the sheets, and means for rotating the overlapping members at a greater peripheral speed than the rate of travel of the conveyors.
29. A sheet-controlling apparatus comprising separate endless traveling conveyors, rotatable overlapping members extending between the conveyors for engagement with the sheets, and a gate contacting with the sheets in advance of the overlapping members.
30. A sheet-controlling apparatus comprising separate endless traveling conveyors, and rotatable overlapping members extending between the conveyors for engagement with the sheets and constructed and arranged to support the conveyors and thereby nullify the overlapping function.
31. A sheet-overlapping apparatus comprising separate endless traveling conveyors having upper and lower runs, a shaft extending between the runs of the conveyors, rolls carried by the shaft and arranged to extend between the upper runs of adjacent conveyors, opposite bearing blocks for the shaft, and means arranged to move the bearing blocks simultaneously.
32. A sheet-overlapping apparatus comprising separate endless traveling conveyors having upper and lower runs, a shaft extending between the runs of the conveyors, rolls carried by the shaft and arranged to extend between the upper runs of adjacent conveyors, opposite bearing-blocks for the shaft, a pulley fixed to the shaft, a guide-pulley rotatable upon the bearing-block, and a driving belt operating over said pulleys.

Signed at Boston, in the county of Suffolk and State of Massachusetts, this first day of July, 1921.

HARMON E. LINDBLADH.
